CHARLES CANYOCK
By *Victor J. Evans*
Attorney.

UNITED STATES PATENT OFFICE

CHARLES CANYOCK, OF SAN FRANCISCO, CALIFORNIA

CUSPIDOR LID

Application filed May 31, 1930. Serial No. 458,409.

This invention relates to improvements in cupidors.

The principal object of this invention is to produce a cuspidor which has a self-closing cover and one which may also be opened through the action of a foot-lever.

A further object is to produce a cuspidor or similar vessel wherein the contents thereof will be, under normal conditions, hidden from public view.

A further object is to produce a device which is simple in construction and economical to manufacture, and extremely sanitary.

Other objects and advantages will be apparent during the course of the following description.

In the accompanying drawings forming a part of this specification and in which like numerals are employed to designate like parts throughout the same,

Figure 1 is a top plan view of my device,

Figure 2 is a side elevation of Figure 1,

Figure 3 is a fragmentary rear elevation of Figure 1.

There are many vessels, which, if, provided with covers would present a much more sightly appearance, as for instance cupidors, and like refuse receiving containers.

It is often desired to use these vessels and in order to do so, if they are provided with a cover, the cover must be raised to give access thereto. Applicant has therefore provided a simple means of raising the cover in a quick manner even when the hands are occupied and could not be used to raise the same.

In the accompanying drawings wherein for the purpose of illustration is shown a preferred embodiment of my invention, the numeral 5 designates the body of a receptacle such as a cuspidor, this body has a cover 6 hinged thereto as shown at 7. The pintle of the hinge is extended as shown at 8 and bent as at 9 so as to form a crank-arm to which may be attached a rod 11, to which a foot piece 12 is secured. A spring 13 has one end connected to the pintle of the hinge and has its opposite end connected to one of the hinged securing bolts as shown at 14.

It is to be understood that the form of my

invention herewith shown and described is to be taken as a preferred example of the same and that various changes relative to the material, size, shape and arrangement of parts may be resorted to without departing from the spirit of the invention or the scope of the subjoined claim.

Having thus described my invention, I hereby claim:

In a device of the character described, a receptacle, a cover hinged to said receptacle, said hinged construction including an elongated pintle, a bend formed in said pintle and defining a crank arm, a spring supported on said hinge and having one end thereof secured to the hinge pintle and the opposite end thereof to the base of the hinge, and a pedal suspended from said crank arm whereby upon actuation thereof the cover of said receptacle may be moved.

In testimony whereof I affix my signature,

CHARLES CANYOCK.
